RATION OF RHODE ISLAND.

SAFETY DEVICE FOR ELEVATORS.

1,122,497.

Specification of Letters Patent. Patented Dec. 29, 1914.

Application filed March 9, 1907. Serial No. 361,570.

To all whom it may concern:

Be it known that we, ROBERT FREER and SAMUEL GREER, both of Providence, county of Providence, and State of Rhode Island, have invented certain new and useful Improvements in Safety Devices for Elevators; and we do hereby declare the following specification, taken in connection with the accompanying drawings, forming a part of 10 the same, to be a full, clear, and exact description thereof.

The object of the present invention is to provide means whereby the power for operating the elevator will be shut off whenever 15 any one of the doors of the elevator-well is opened or is moved from its closed position, and whereby the car cannot be started until such door has been closed.

To that end the invention consists primarily in the combination, with the starting and stopping mechanism of the elevator, of a device adapted to operate said mechanism to shut off the power whenever a door of the elevator-well is opened or is moved 25 from its closed position, and adapted to be operated by said elevator-door in closing to turn on the power.

The invention further consists in the combination, with the starting and stopping mechanism of the elevator, of a series of such devices each adapted to be operated by one of the doors of the elevator-well, and so that when any one of said doors is opened or partially opened the power will be shut off, and so that the closing of any door which has thus been opened or partially opened will serve to turn on the power.

The invention may be employed in connection with any form of elevator operating mechanism, as for example, with a plunger elevator, or with a hydraulic elevator of the so-called Otis type, or with an electric elevator.

In the accompanying drawings the invention is shown as employed in connection with a plunger-elevator.

In the case of such plunger-elevator the invention further involves the combination, with the main operating valve, of a cut-off valve adapted to cut off the fluid-pressure. Such cut-off valve may, if desired, be located between the fluid-pressure supply and the main operating valve, and so as to cut off the fluid-pressure on the supply side of

said valve. It is preferred, however, to locate said cut-off valve on the exit side of the main operating valve, and between said operating valve and the cylinder of the elevator-plunger, and it is so shown in the drawings. As said cut-off valve is necessarily of such a character as to require considerable power to operate the same, it is desirable to make use of the fluid-pressure for this purpose, and to that end the invention further consists in the combination, 55 with said cut-off valve, and with the devices operated by the doors of the elevator-well, of a pilot-valve or controlling-valve, the operation of said controlling-valve being controlled by the doors of the elevator-well, 60 and said controlling-valve serving in turn to control the operation of the cut-off valve.

The invention further consists in the combinations and arrangements of parts herein-after described and claimed. 75

Referring to the drawings, Figure 1 is an elevation showing the invention applied in connection with a plunger-elevator, and with three doors for the elevator-well located at a corresponding number of floors. 80 Fig. 2 is an elevation on an enlarged scale of the device adapted to be operated or controlled by the door of the elevator-well. Fig. 3 is a section on the line $x-x$ of Fig. 2. Fig. 4 is a plan view of the device shown in 85 Fig. 2. Fig. 5 is a longitudinal section of the pilot-valve on an enlarged scale.

Referring to Fig. 1, the cylinder for the elevator-plunger is represented at 1. 2 represents the elevator-plunger, and 3 is the 90 car, which for convenience is shown simply as a platform-elevator, such as commonly employed for freight purposes. 4 represents the fluid-pressure supply-pipe, 5 the main operating-valve, 5^a the exhaust pipe 95 therefrom, 6 the operating-mechanism for said valve, and 7 the operating cable, which extends up through the car, and by means of which the main valve is operated from the car, all of these parts being of the usual 100 or any desired construction. The cut-off valve 8 is located in the pipe 8^a which leads from the main operating valve 5 to the cylinder 1. This cut-off valve may be of any suitable construction adapted to operate to 105 cut off the fluid-pressure from the cylinder 1, and thus to control the operation of the elevator. As shown in the drawings, said

cut-off valve 8 is adapted to be operated by fluid-pressure admitted through the pipes 9 and 10. The pipe 9 connects with any suitable fluid-pressure supply, and in the arrangement shown is connected with the lower end of the valve-casing of the valve 8, while the pipe 10 is connected with the upper end of said valve-casing. The valve 8 is a differential valve, and the fluid-pressure entering the valve-casing through the pipe 9 acts constantly upon the smaller area of said valve 8, and serves to hold said valve open at all times when the fluid-pressure through the pipe 10 is cut off. The fluid-pressure is intermittently admitted to the opposite end of the valve-casing through the pipe 10, and when so admitted acts upon the larger area of the valve 8, and so as to overcome the pressure admitted through the pipe 9 and acting upon the smaller area of said valve, and thereby move said valve to close the same and thus cut off the fluid-pressure from the plunger-cylinder 1, even if the main operating valve 5 be open. The pipes 9 and 10 communicate with the valve-casing of the pilot-valve 11, from which casing also extends the exhaust-pipe 12. The valve-casing of said pilot-valve is provided with suitable ports 9^a, 10^a and 12^a with which the pipes 9, 10 and 12 respectively communicate. Said pilot-valve comprises a valve-stem 11^a which is reduced in diameter at two different places, so as to form the valve 11^b and 11^c, the valve 11^b being the main controlling-valve which controls the three ports 9^a, 10^a and 12^a. Thus with the valve 11^b in one position communication is opened between the port 10^a and the port 9^a, and so that the fluid-pressure will flow from the pipe 9 to the pipe 10 and thence to the upper end of the valve casing of the cut-off valve 8, while with the valve 11^b in its other position communication between the port 10^a and the port 9^a will be cut off and communication between the port 10^a and the exhaust-port 12^a will be opened, and so that the fluid-pressure may be released and exhausted from the upper end of the valve-casing of the cut-off valve 8 through the pipe 10 and the exhaust-pipe 12. The pilot-valve 11 is provided with a spring 13 which normally holds the valve 11^a in a position to cut off the flow of the fluid-pressure from the pipe 9 to the pipe 10 and thus to cut off the fluid-pressure from the larger area of the valve 8. Said spring is permitted to so act only when all the doors of the elevator-well are closed, as will be hereinafter explained. Connected to the valve-stem of the controlling-valve 11 is a cable or wire 14 which extends to the top of the elevator-well and has its upper end secured to the ceiling or to some fixed part. Preferably a spring 15 is connected to the upper end of the cable 14, the principal purpose of

said spring being to overcome or counter-balance the weight of the wire which, particularly in the case of a tall building, will be very considerable. Secured to the jamb of each of the doors of the elevator-well is a plate 16 on which is pivoted a bell-crank lever 17. The arm 18 of said lever is forked or provided with an aperture 19 through which the cable 14 passes. Secured to the cable 14 above the arm 18 of said lever is a block 20 adapted to be engaged by said arm 18. The arm 21 of the lever 17 extends somewhat beyond the jamb of the door, and so that the free end of said arm will be in a position to be engaged by the door of the elevator-well as said door is moved to its closed position. Preferably the free end of the arm 21 is rounded more or less as shown. The plate 16 is provided with a projecting boss 22 which is tapped to receive a screw 23. Said screw 23 is made hollow to receive a coiled spring 24, as shown in Fig. 3. Inserted in the upper end of the hollow screw 23 is a plunger 25, the upper end of which is arranged to bear against the underside of the arm 18 of the lever 17. Preferably the arm 18 is provided with a conical recess 26, and the upper end of the plunger 25 is made more or less pointed to enter such recess. A pin or stud 27 projects from the plate 16 above the arm 18, and serves to limit the upward movement of said arm under the action of the spring 24. The tension of the spring 24 may be adjusted by turning the screw 23, and when the adjustment has been made, said screw 23 may be held in adjusted position by the set screw 28. In the drawings a building of three stories is represented or indicated, and consequently three doors 29, 29^a, 29^b of the elevator-well are shown, the door 29 being shown as open and showing the opening 30 into the elevator-well, while the doors 29^a and 29^b are shown as closed.

The operation of the apparatus above described is as follows: Assuming all of the doors of the elevator-well to be closed, which may be regarded as the normal position, it will be understood that any one of the doors in closing comes into engagement with the overhanging end of the arm 21 of the lever 17, and that the final closing movement of the door acts to depress the arm 18 of said lever against the action of the spring-pressed plunger 25 and its spring 24, and it will be further understood that so long as all of the doors remain closed all of the arms 18 will be held depressed and out of engagement with their respective blocks 20 on the wire 14. With all of the arms 18 thus out of engagement with their coacting blocks 20, the spring 13 of the pilot-valve 11 will be free to act, and under the action of said spring the pilot-valve 11 will be moved to and held in a position to cut off the passage of the fluid- 130

pressure through said valve, and thus to cut off the fluid-pressure from the larger area of the cut-off valve 8, as hereinbefore explained. With the fluid-pressure thus cut off from the larger area of the cut-off valve 8, the fluid-pressure entering the valve-casing of said valve through the pipe 9 and constantly acting upon the smaller area of said valve 8 will serve to move said valve 19 to, and hold it in, a position to open the passage through the pipe 8^a. With the valve 8 in this position, and with the pipe 8^a open, the fluid-pressure may flow from the supply-pipe 4 to the plunger-cylinder 1 15 whenever the main operating valve 5 is opened, or in other words, the car may at any time be started by a proper manipulation of the main operating valve 5, by means of the operating cable 7. If now any one 20 of the doors of the elevator-well be opened or partially opened, so that said door is moved out of engagement with the arm 21 of the lever 17, this will serve to release the spring 24 and permit the spring-pressed 25 plunger 25 to act upon the arm 18 of said lever to raise said arm. The raising of said arm 18 will, by its engagement with the block 20, cause an upward pull on the wire 14. Such movement of the wire 14 will 30 operate to overcome the tension of the spring 13 and to move the pilot-valve or controlling-valve 11 so as to permit the passage of the fluid-pressure from the pipe 9 through said valve to the pipe 10, and thence to the 35 casing of the cut-off valve 8 to act upon the larger area of said valve. The fluid-pressure thus acting upon the larger area of the valve 8 will overcome the pressure on the smaller area of said valve, and will thus 40 serve to close said valve 8 and thus to close the passage through the pipe 8^a. So long as the door of the elevator-well remains open or out of engagement with the arm 21, the cut-off valve will be held in its closed position 45 and so that the fluid-pressure will be cut off from the plunger-cylinder, and so that consequently the car cannot be started, even though the main operating valve 5 be opened. When, however, the door is closed, 50 the engagement of the door with the arm 21 will serve to depress the arm 18, thereby removing the end of said arm out of engagement with its block 20, which will serve to permit the spring 13 of the pilot-valve 11 55 to act to close said valve, and so as to shut off the fluid-pressure from the pipe 10 and from the larger area of the cut-off valve 8. The fluid-pressure, which is constantly acting upon the smaller area of said valve 8, 60 will then operate to open said valve and so as to permit the starting of the elevator.

It will be seen that, with the construction above described, whenever any one of the doors of the elevator-well is moved from 65 its closed position, the power for starting

the car will be cut off automatically, and so that the car cannot be started so long as any one of the doors remains thus unclosed. It will be further seen that the power will be thus automatically cut off, and so that 70 the car cannot be started, not only when any one of the doors is opened or partially opened, but also if any one of the doors is left unlatched. Thus if one of the doors be left unlatched, the weight of the door itself will not be sufficient to overcome the force of the spring 24, which is a comparatively powerful spring, and the spring-pressed plunger 25, acting on the lever 17, will operate to raise the wire 14 to operate 75 the controlling valve 11, as above described, the arm 21 of said lever at the same time serving to move back the door a sufficient distance to permit the operation of said controlling valve. 85

While we have shown the invention as applied to a plunger-elevator, it will be understood that the invention may likewise be applied to other forms of elevators, as for example to a hydraulic elevator of the Otis 90 type, or to an electric elevator. If the invention is to be applied to a hydraulic elevator of the character referred to, the pilot-valve 11 and the cut-off valve 8 may be employed, as in the case of the plunger-elevator 95 shown, said cut-off valve being then employed to cut off the fluid-pressure from the operating cylinder. If the invention is to be applied to an electric elevator, however, the pilot-valve 11 and cut-off valve 8 may be 100 dispensed with, and the wire 14 connected to a secondary or cut-off switch to be arranged in the operating electric circuit in addition to the main operating switch.

While we have shown the cut-off valve 8 105 located between the main operating valve and the plunger-cylinder, it will be understood that said cut-off valve may, if desired, be located between the supply-pipe and the main operating valve. It will also be understood 110 that the construction and arrangement of the parts may be varied without departing from the main features of the invention.

What we claim as our invention and desire to secure by Letters Patent is:

1. A device for controlling a cable comprising a lever, a spring-pressed plunger adapted to engage said lever, and a stop for limiting the movement of said lever under the action of said spring-pressed plunger. 115

2. A device for controlling a cable comprising a lever, a spring-pressed plunger adapted to engage said lever, an adjusting screw for adjusting the spring of said plunger, and a stop for limiting the movement of said lever under the action of said spring-pressed plunger. 120

3. A device for controlling a cable comprising a plate adapted to be secured to a door-jamb, a lever pivoted on said plate, a 130

spring-pressed plunger mounted on said plate and adapted to engage said lever, an adjusting screw for adjusting the spring of such plunger, and a stop for limiting the movement of said lever under the action of said spring-pressed plunger.

4. The combination, with an elevator-car and a door, of a main controlling device for controlling the operation of said car, a cut-off device for cutting off the power, a cable for controlling said cut-off device, a spring

adapted to move said cable in one direction, a lever adapted to move said cable in the opposite direction, and a spring-pressed plunger adapted to act on said lever, the action 15 of said spring-pressed plunger being controlled by said door.

ROBERT FREER.
SAMUEL GREER.
